TRAFFIC PROTECTION APPARATUS

Harold G. Witmer, Edgewood, Pa., assignor to
The Union Switch & Signal Company, Swiss-
vale, Pa., a corporation of Pennsylvania

Application April 22, 1946, Serial No. 663,836

7 Claims. (Cl. 246—34)

1

My invention relates to traffic protection apparatus, and particularly to apparatus for providing crossover protection for trains moving along railway tracks which are connected with each other by a crossover track through hand-operated track switches.

A requisite for crossover protection apparatus is that it must be so arranged that a car or locomotive, while occupying a crossover such, for example, as one connecting two main tracks, while the switches are in the normal position for train movements along the main tracks, will cause a signal for each main track to indicate stop if the car or locomotive is within fouling distance of that main track. In crossover protection schemes embodying track circuits, one characteristic should therefore be high shunting sensitivity in order to insure that the crossover track circuits will be shunted if the crossover track has high contact resistance due to infrequent train movements over the crossover.

One feature of my invention is the provision of two coded track circuits for one crossover, which inherently have higher shunting sensitivity than non-coded track circuits which have the same normal battery voltage. A further feature of my invention is the provision of one polar stick relay having two control windings insulated from each other, one of which is energized by current from one of the track circuits, and the other of which is energized by current from the other track circuit.

The apparatus of my invention is an improvement over that which is disclosed in the copending application, Serial No. 671,191, filed May 21, 1946, by Lowell B. Yarbrough for Traffic Protection Apparatus.

I shall describe two forms of apparatus embodying my invention, and shall then point out the novel features thereof in claims.

In the accompanying drawings, Fig. 1 is a diagrammatic view showing one form of apparatus embodying my invention, in which the two track sections of a crossover track are energized alternately by current controlled by a coding device; and Fig. 2 is a diagrammatic view showing a modified form of the apparatus of Fig. 1, in which the two track sections are energized alternately by current controlled by contacts of the polar stick relay.

Similar reference characters refer to similar parts in each of the views.

Referring first to Fig. 1, a stretch of railway is shown comprising two tracks, designated by the reference characters 1T and 2T, connected with

each other by a crossover track designated by the reference character 3T, through hand-operated switches 1W and 2W. Track 3T is divided, by means of insulated joints 4, into two sections a—b and b—c.

Each of the sections a—b and b—c is provided with a track circuit completely insulated from the track circuit for the other of these two sections, each including a suitable source of current, such for example as a battery 1Q or 2Q, respectively, connected through a variable resistor 6 or 15, respectively, and a contact 5 or 16, respectively, of a coding device CT across the rails 3a and 3b adjacent the end of its section at the midpoint b of track 3T.

Contacts 5 and 16 of coding device CT are simultaneously closed, alternately at their front and back points. The operating frequency at which coding device CT closes its contacts 5 and 16 may be of any suitable magnitude such, for example, as 180 cycles per minute.

Coding device CT is constantly energized by a suitable source of current having terminals B and N, and therefore its contacts 5 and 16 are repeatedly operated, alternately at their front and back points. Battery 1Q is connected through the front point of contact 5, whereas battery 2Q is connected through the back point of contact 16. The track circuit for section a—b is therefore repeatedly energized by a pulse of current while the track circuit for section b—c is without energy, and the track circuit for section b—c is repeatedly energized by a pulse of current while the track circuit for section a—b is without energy.

Each of the track circuits for sections a—b and b—c also includes a winding 9 or 12, respectively, of a polar stick relay R, and normally closed contacts operated by switch 1W or 2W, respectively, and also a variable resistor 8 or 13, respectively, shown adjacent the windings of relay R. Windings 9 and 12 are electrically insulated from each other. I shall assume that these windings are so arranged that relay R, in response to energization of winding 9 from the rails of section a—b, closes its polar contacts 17 and 21 in their right-hand position, and in response to energization of winding 12 from the rails of section b—c, closes contacts 17 and 21 in the left-hand position, as shown in the drawing.

While track 3T is unoccupied and switches 1W and 2W are in the normal position as shown in the drawing, portions 18 and 19 of primary winding m of a decoding transformer F are repeatedly energized alternately and in opposite directions.

by current controlled by contact 17 of relay R. Alternating current of low frequency is therefore generated in secondary winding *d* of transformer F, and is rectified by contact 21 of relay R. The current thus rectified energizes a code detecting relay RP which controls signals for governing traffic movements over tracks 1T and 2T.

Referring now to Fig. 2, the apparatus here shown differs from that of Fig. 1 in that the current supplied to the track circuits is controlled by polar contacts 25 and 26 of relay R instead of by contacts of a separate coding device CT; and relay R is made slow acting by some suitable means such, for example, as electrolytic condensers 27 and 28 connected in multiple with the relay windings 9 and 12, respectively. In this arrangement, relay R therefore serves as the code transmitter for coding the current supplied to the track circuits.

Having described, in general, the arrangement and operation of the apparatus, I shall now describe its operation more in detail.

As shown in the drawings, all parts are in the normal condition; that is, switches 1W and 2W are in their normal position; crossover track 3T is unoccupied; coding device CT is constantly energized, and its contacts 5 and 16 are therefore being repeatedly operated between their front and back points as shown in the drawings; windings 9 and 12 of relay R are being energized alternately; transformer F and relay RP are, in turn, energized; and contacts 23 and 24 of relay RP are closed in signal control circuits for tracks 1T and 2T.

In the apparatus shown in Fig. 1, each time when contact 5 closes at its front point, a circuit is closed for energizing winding 9 of relay R, this circuit passing from the positive terminal of battery 1Q, through the front point of contact 5 of coding device CT, variable resistor 6, rail 3b of track section *a*—*b*, contact 7 of switch 1W closed in its normal position, variable resistor 8, winding 9 of relay R, contact 10 of switch 1W closed in the normal position, and rail 3a of section *a*—*b* back to battery 1Q. Each time when contact 16 closes at its back point, a circuit is closed for energizing winding 12 of relay R, this circuit passing from the positive terminal of battery 2Q, through rail 3b of section *b*—*c*, contact 11 of switch 2W closed in the normal position, winding 12 of relay R, variable resistor 13, contact 14 of switch 2W closed in the normal position, rail 3a of section *b*—*c*, variable resistor 15, and contact 16 of coding device CT back to battery 2Q.

Each time when winding 9 is energized, relay R moves its contacts 17 and 21 to the right-hand position, and each time when winding 12 is energized, relay R moves its contacts 17 and 21 to the left-hand position in which they are shown in the drawings. When contact 17 is closed in the left-hand position, a circuit is closed for energizing portion 18 of primary winding *m* of transformer F, this circuit passing from terminal B, through contact 17 of relay R closed in the left-hand position, and portion 18 of winding *m* to terminal N. When contact 17 is closed in the right-hand position, a circuit is closed for energizing portion 19 of primary winding *m* of transformer F, this circuit passing from terminal B, through contact 17 of relay R closed in the right-hand position, and portion 19 of winding *m* to terminal N. The portion 19 of winding *m* thus becomes energized in the opposite direction from that in which portion 18 has been energized.

Low frequency alternating current is therefore generated in the secondary winding *d* of transformer F, and is rectified in a well-known manner by the operation of contact 21 of relay R. Relay RP is energized by this rectified current, and hence its contacts 23 and 24 are closed in the signal control circuits.

If switch 1W is placed in the reverse position, its contacts 7 and 10 will disconnect winding 9 of relay R from section *a*—*b*, and will place a shunt across this winding. If a train enters section *a*—*b*, winding 9 becomes shunted, causing winding 9 to be deenergized. Under either of these conditions, contacts 17 and 21 of relay R will be operated to their left-hand position in response to energization of winding 12, and will remain in that position until winding 9 again becomes energized after the train leaves section *a*—*b* and switch 1W is restored to its normal position.

Similarly, if switch 2W is moved away from its normal position or if a train enters section *b*—*c*, winding 12 of relay R will become deenergized. In either of these instances, contacts 17 and 21 will be operated to their right-hand position in response to energization of winding 9, and will remain in that position until winding 12 again becomes energized.

If both windings 9 and 12 should become deenergized, contacts 17 and 21 will remain in the position to which they were last previously operated, until one or both of windings 9 and 12 shall again become energized.

When contact 17 remains continuously in one position or the other, only one of the portions 18 and 19 of primary winding *m* of transformer F will be energized, so that winding *m* will be energized by current flowing in only one direction. Under this condition, no current will be generated in secondary winding *d* of transformer F, and hence relay RP will be deenergized and its contacts 23 and 24 will be opened, causing signals for tracks 1T and 2T to indicate stop.

In the modification of the apparatus shown in Fig. 2, with contact 25 of relay R closed in the left-hand position as shown in the drawing, a circuit is completed for energizing winding 9 of relay R, this circuit passing from the positive terminal of battery 1Q, through contact 25 of relay R closed in the left-hand position, rail 3a of section *a*—*b*, contact 10 of switch 1W closed in the normal position, variable resistor 8, winding 9 of relay R in multiple with condenser 27, contact 7 of switch 1W closed in the normal position, rail 3b of section *a*—*b*, and variable resistor 6 back to battery 1Q. In response to energization of winding 9, relay R will operate its polar contacts 17, 21, 25 and 26 to the right-hand position. With contact 26 closed in the right-hand position, a circuit is completed for energizing winding 12 of relay R, this circuit passing from the positive terminal of battery 2Q, through variable resistor 15, rail 3a of section *b*—*c*, contact 14 of switch 2W closed in the normal position, variable resistor 13, winding 12 of relay R in multiple with condenser 28, contact 11 of switch 2W closed in the normal position, rail 3b of section *b*—*c*, and contact 26 of relay R closed in the right-hand position, back to battery 2Q. In response to the energization of winding 12, relay R will operate its polar contacts 17, 21, 25 and 26 back to the left-hand position. Winding 9 will then again be energized, and the operations just traced will be repeated.

The positioning of the polar contacts of relay

R in the event of deenergization of either or both of the windings 9 and 12 of relay R will be the same as already described for Fig. 1. The energization of transformer F and relay RP also occurs in the manner described for Fig. 1.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In combination, a stretch of railway track divided into two sections, a coding device having two contacts repeatedly operated at the same time alternately to a first position and a second position while said coding device is energized, means controlled by one of said contacts in its first position for supplying coded current to the rails of one of said sections, means controlled by the other of said contacts in its second position for supplying coded current to the rails of the other section, a polar stick relay having two control windings insulated from each other and one of which is connected across the rails of said one section and the other of which is connected across the rails of said other section, two polar contacts each closed in a first position by said polar stick relay in response to energization of said one winding and each closed in a second position by said polar stick relay in response to energization of said other winding, a decoding transformer, means controlled by one of said polar contacts for energizing the primary winding of said transformer alternately in opposite directions, means controlled by the other polar contact for rectifying the current output from the secondary winding of said transformer, and traffic governing means controlled by said rectified current.

2. In a crossover protection scheme in which a crossover track is divided into two sections, the combination comprising, means for supplying coded current to the rails of one of said sections alternately with the rails of the other section, a polar stick relay energized by current from the rails of one of said sections controlled by one of the track switches for said crossover track in its normal position and energized by current from the rails of the other section controlled by the other track switch for said crossover track in its normal position, two polar contacts each closed in a first position by said polar stick relay in response to energization by current from the rails of said one section and each closed in a second position by said polar stick relay in response to energization by current from the rails of said other section, and traffic governing means controlled by said polar contacts.

3. In combination, a stretch of railway track divided into two sections, means for supplying coded current to the rails of one of said sections alternately with the rails of the other section, a polar stick relay energized by current from the rails of one of said sections and alternately by current from the rails of the other section, two polar contacts each closed in a first position by said polar stick relay in response to energization by current from the rails of said one section and each closed in a second position by said polar stick relay in response to energization by current from the rails of said other sec-

tion, and traffic governing means controlled by said polar contacts.

4. In combination, a stretch of railway track divided into two sections, a polar stick relay having a plurality of polar contacts operable simultaneously to a first position in response to energization of said polar stick relay by current from the rails of one of said sections and also operable simultaneously to a second position in re-

10 sponse to energization of said polar stick relay by current from the rails of the other section, means controlled by one of said contacts in its first position for supplying current to the rails of said other section, means controlled by another of said contacts in its second position for supplying current to the rails of said one section, and means controlled by said polar stick relay for controlling traffic governing means.

5. In combination, a stretch of railway track 20 divided into two sections, a polar stick relay having a plurality of polar contacts operable simultaneously to a first position in response to energization of said polar stick relay by current from the rails of one of said sections and also oper-

25 able simultaneously to a second position in response to energization of said polar stick relay by current from the rails of the other section, means controlled by one of said contacts in its first position for supplying current to the rails of said other section, means controlled by another of said contacts in its second position for supplying current to the rails of said one section, and means controlled by said polar stick relay for controlling traffic gov-

30 erning means.

6. In combination, a stretch of railway track 35 divided into two sections, means for repeatedly supplying a pulse of current to the rails of one of said sections alternately with a pulse of current to the rails of the other of said sections, a polar stick relay having two windings one of which is controlled by energy received from said one section and the other of which is controlled by energy received from said other section in response to said pulses of current for operating polar contacts of said relay to a first or a second position respectively, and traffic governing means controlled by said relay.

7. In combination, a stretch of railway track 50 divided into two sections, means for repeatedly supplying a pulse of current to the rails of one of said sections alternately with a pulse of current to the rails of the other of said sections, a polar stick relay responsive to energy from said pulses received from said one section for closing 55 polar contacts of said relay in a given position and responsive to energy from said pulses received from said other section for closing said polar contacts in the opposite position, and traffic governing means controlled by said polar contacts of said relay.
